TABLE ATTACHED INFANT'S CHAIR

Francis E. Ducey, Midland, Mich.

Application November 23, 1945, Serial No. 630,246

6 Claims. (Cl. 155—78)

1

This invention relates to infants' chairs and more particularly to an improved chair adapted for attachment to a table or other article of household furniture.

One of the prime objects of the invention is to design an inexpensive and durable infant's chair which can be detachably mounted on a table or other support, and from which the occupant can be readily removed and/or placed in position therein.

Another object is to design an infant's chair, the rear seat section of which is pivotally connected to the front section to facilitate the placing or removal of the infant in the chair.

A further object is to provide a lightweight neat-appearing chair structure that can be readily handled and applied, and which can be easily and economically manufactured and assembled.

A further object still is to provide a chair having a telescopic connection intermediate its length so that it can be adjusted to suit various types and designs of supports.

With the above and other objects in view, the present invention consists in the combination and arrangement of parts, hereinafter more fully described, illustrated in the accompanying drawing, and more particularly pointed out in the appended claims, it being understood that changes may be made in the form, size, proportion and minor details of construction without departing from the spirit or sacrificing any of the advantages of the invention.

In the drawing:

Fig. 1 is a side-elevational view of my infant's chair showing it attached to a table which is shown in section.

Fig. 2 is a top plan view with the table omitted, the broken lines showing the seat section of the frame swung to facilitate placing and/or removal of the infant from the chair.

Fig. 3 is an enlarged, fragmentary view illustrating the telescopic connection.

Fig. 4 is an enlarged, detail showing the seat locking member.

Fig. 5 is a transverse-sectional view taken on the line 5—5 of Fig. 3.

Fig. 6 is an enlarged, sectional, plan view showing the hinge connection.

Refer now more particularly to the accompanying drawing in which I have shown one embodiment of my invention.

The frame proper is preferably made up of square tubing formed of one of the lighter metals such as magnesium or the like, the front end comprising a horizontally disposed section 5 bent

2

vertically at the front end as at 6, thence being bent horizontally and transversely of the frame as at 7, this section 7 engaging the lower face of a table T or other support, and a non-metallic sleeve 8 is provided thereon and is formed of rubber, fabric, or similar material to prevent slippage and marring of the surface with which it comes into contact.

A telescopic connection 9 is provided intermediate the length of the chair frame; the member 5 telescoping into the section 10; and spaced-apart openings 11 are provided in the end section of the tubes; a pin 12 being inserted in the aligned openings for securing the sections in set position as shown.

The horizontal section 10 is bent upwardly as shown at 13, thence horizontally as at 14, thence extending transversely as at 15, thence rearwardly as at 16 to form a side parallel to the section 14, thence transversely and being welded to the section 14 to form a rigid structure on which a tray 17 can be placed, non-metallic sleeves 18 being provided on the sections 14 and 16 to eliminate marring and/or slippage.

The seat frame is also formed of tubing and comprises a pair of spaced-apart side frames 19 and 20 respectively, connected at their lower front ends by means of the horizontally disposed bar member 21. A panel 22 connects the rear ends of the side frames. A seat 23 spans the frames 19 and 20 and is secured thereto in any approved manner, spaced-apart tube members or strips 24 connecting the upper and lower sections 25 and 26 of the side frames in the conventional manner.

The seat frame is hingedly connected to the front section 13, the vertical section 27 being disposed in parallel relation thereto to permit it to swing as clearly indicated in broken lines in Fig. 2 of the drawing, spaced-apart hinges 28 being provided as shown.

A strap 29, formed of spring steel or similar material, is riveted to the frame section 26 as shown, the forwardly projecting end of the strap being disposed in contact with the member 10, and a U-shaped section 30 is provided on the end as shown, said section hooking over the section 10 to secure the seat frame in position and in proper alignment with the front end 5 of the frame.

The tray is easily removable for washing and cleaning, and the infant can be easily placed in or removed from the chair. There is free and unobstructed access to the seat, and there are no

bars or obstructions in which the infant's legs may become entangled.

While in the present instance I have shown the frames formed of square tubing, it will, of course, be obvious that these may be tubular or any other shape desired.

From the foregoing, it will be understood that I have perfected a simple, convenient and economical lightweight chair that can be readily attached and/or detached from a support and in which the infant may be readily placed and/or removed.

What I claim is:

1. An infant's chair of the class described comprising, a frame adapted to be detachably mounted on a table, the front end section of the frame being formed with a horizontally disposed leg section bent at the front end to extend vertically and bearing against the under side of the table, a U-shaped frame section overhanging the table and bearing on the upper face thereof, a seat frame hingedly connected to the front section, and resilient means on the seat frame and engageable with the front end section of the frame for securing the front section and the seat frame in aligned relation.

2. An infant's chair of the class described comprising, a front frame adapted to be detachably mounted on a table and including a forwardly projecting horizontal leg having an end section bent to extend vertically adapted to bear against the lower face of said table, a rear frame having spaced side frames hingedly connected at one side only to said front frame, a seat in said rear frame, and means on the rear frame and detachably engageable with the forwardly projecting leg to limit swinging of frames in one direction to aligned positions.

3. The combination as defined in claim 2 in which the detachable leg-engaging means comprises an open C-shaped clamp adapted to re-

leasably embrace the forwardly projecting leg at a point intermediate its length.

4. The combination defined in claim 2 in which the forwardly projecting leg comprises an extensible section, and means for securing said leg in adjusted positions.

5. The combination defined in claim 2 in which the front frame includes a rectangular portion overhanging the rear portion of the forwardly projecting leg and bears on the upper face of the table support, and a tray mounted in said U-shaped portion.

6. An infant's chair of the class described comprising, a rigid main frame including a horizontally disposed tray supporting structure engageable on the upper face of a flat supporting structure, horizontally disposed forwardly projecting members below said tray support and forming part of said main frame, a vertically disposed section on the free end of said forwardly projecting members for engagement with the lower face of said support, a seat frame secured to said main frame and including spaced side frames, a back panel spanning and connecting said side frames, said seat frame being hingedly connected, at its one side, to said main frame to swing about said hinge connection and facilitate placing in or removing an occupant from said chair.
